UNITED STATES PATENT OFFICE.

VICTOR BEAUREGARD, OF BOSTON, MASSACHUSETTS.

EMBROIDERY-HOOP.

1,072,687.

Specification of Letters Patent.

Patented Sept. 9, 1913.

Application filed February 13, 1913. Serial No. 748,075.

To all whom it may concern:

Be it known that I, VICTOR BEAUREGARD, a citizen of the United States, residing at Boston, in the county of Suffolk and State 5 of Massachusetts, have invented a new and useful Improvement in Embroidery-Hoops, of which the following is a specification, reference being had therein to the accompanying drawings.

10 This invention relates to embroidery hoops in which two concentric hoops are employed for holding the fabric between them; the outer hoop being provided with means for compressing it against the inner hoop.

15 The object of my invention is to provide means for compressing the outer ring which is light, strong and durable and upon which the embroidery thread cannot catch.

20 In the accompanying drawings Figure 1 is a plan view of an embroidery hoop constructed and operated in accordance with my invention and Fig. 2 is a view on an enlarged scale partly in elevation and partly 25 in section looking upwardly on line 2—2 in Fig. 1.

25 Referring to the drawings, 3 designates an inner closed hoop and 4 an outer divided hoop. The hoops are concentric and the divided hoop is provided with clamping means whereby it may be compressed on the closed hoop.

30 On one end 5 of the divided hoop is mounted a screw-member 6 having its free 35 end provided with a screw thread 7 and being flattened at its other end 8. The screw-member is fastened to the hoop by suitable eyelets 9.

35 Upon the other end 10 of the hoop 4 is mounted a screw-head 11 having a central bore 12 provided with an interior screw-thread and adapted to receive the screw-member 6 mounted on the other end of the 45 hoop. The screw-head has a flange 13 and is mounted in a collar or ring 14 carried by a plate 15 fastened to the hoop by eyelets 16. A finger piece 17 is forced upon the screw-head after the latter is mounted in the collar 14 and thereby serves both as a 50 finger piece to operate the screw-head and as a lock to prevent the screw-head being withdrawn from the collar 14.

55 The operation of my device is as follows: The end of the screw-member 6 is brought into engagement with the central bore 12 of the screw-head 11 and the latter is then

turned and screwed up on the former until the outer hoop 4 is compressed upon the inner hoop 3. When in use the two hoops are operated in the usual manner the fabric being spread over the inner hoop and held 60 between the two hoops.

It will be observed that the clamping means are so constructed that there is no possibility of thread or embroidery silk 65 catching upon any part of the same. All the corners of the screw-head and other parts are rounded off in order that the thread may slip off without being caught.

One important feature of my invention 70 resides in the construction of the screw-head, in that the flange 13 is an integral part of the head. As this flange bears against the collar 14 to prevent the head separating therefrom when the hoop is being 75 clamped it is essential that it have sufficient strength to withstand the repeated strains incidental to the use of embroidery hoops. I have found from experience that if this flange is not made integral with the screw- 80 head, the strain to which it is subjected soon forces it off and the clamping device is thereby rendered useless. Where, however, the flange is made integral with the head, there is no possibility of the head becoming disengaged from the collar 14 and, consequently, my device is very durable and will 85 last indefinitely.

What I claim is:—

1. An embroidery hoop comprising an 90 inner closed hoop and an outer divided hoop provided with means for compressing it upon the inner hoops; said means consisting of a screw-member secured on one end of said divided hoop, a collar fastened to the 95 other end of said hoop and a screw-head having a flange at one end integral therewith and a finger piece; said screw-head being rotatably mounted in said collar and held in place therein by said flange on one 100 side and said finger piece on the other side of said collar.

2. An embroidery hoop comprising an inner closed hoop and an outer divided hoop provided with means for compressing 105 it upon the inner hoop; said means consisting of a screw member fastened to one end and a collar secured to the other end of said divided hoop, a screw-head having a central threaded bore to receive the said screw 110 member and having at its opposite end a flange integral therewith and a finger piece

forced upon the body of said screw-head; said screw-head being rotatably mounted in said collar and held in place thereon by said flange on one side and said finger piece on the other side of said collar.

In testimony whereof, I hereunto set my hand in the presence of two subscribing

witnesses, this the eleventh day of February, 1913.

VICTOR BEAUREGARD.
